UNIVERSAL BOMB HOISTING BAND

Louis F. Mahan, Iowa City, Iowa, and Walter C. Hasselhorn and Eugene H. Ziebold, Chicago, Ill., assignors, by direct and mesne assignments, of two-thirds to Cook Electric Company, Chicago, Ill., a corporation of Illinois, and one-third to Louis F. Mahan

Application May 24, 1943, Serial No. 488,260

11 Claims. (Cl. 294—74)

1

This invention relates to a universal bomb hoisting mechanism for use in lifting various types of bombs, such as aerial bombs, torpedoes, smoke tanks, depth charges, mines, etc., and more particularly to a bomb hoisting band adapted to be readily clamped about a bomb and used in hoisting the bomb during the loading operation and to be thereafter released and removed from the bomb.

The invention particularly contemplates a structure that may be readily used to load practically all types, sizes and shapes of bombs under all known basic hoisting conditions into a shackle or rack suspension with a single or double hoist and in all types of planes or ships.

It will be understood that, among other things, one of the features of the invention resides in the ability quickly to attach the bomb hoisting band herein disclosed to a bomb, and, after the bomb is lifted in position and secured, quickly to detach and drop the bomb hoisting band from about the bomb without requiring the use of tools or excessive effort in cramped quarters on the part of the crew, although the bomb may be located in a position, after it is secured, affording little if any space for the removal of the band.

Many difficult problems arise in the loading of bombs. The space provided for receiving bombs in the bomb bays and under the wings is usually limited and it varies in many of the different types of airplanes now in use. The design of the ship's fuselage and wing section, the pattern of the load to be carried, as well as the different weights and types of bombs to be loaded, are factors that limit the space receiving the bombs and make the loading of bombs difficult. They likewise add to the difficulties encountered in lifting the bombs and in removing the hoisting mechanism after the bombs are secured. Speed is also an essential consideration because loading often occurs between aerial operations of the planes or during refueling and when little time is given as when alarms are sounded and the planes must be conditioned as quickly as possible. The loss of time is a serious matter which is often realized only after a serious mishap and irreparable damage is suffered. It is also essential that the ground crew be able immediately to remove the hoisting band and all its parts after the bombs are loaded in position so that accuracy in the bombing operations is assured and deflection in the descent of the bombs will be avoided.

The invention is directed to providing an improved structure that may be used wherever hoisting bands are required and which can be

2

removed without difficulty to assure that the same will not be left upon the bombs after they are loaded. The invention overcomes the difficulties heretofore experienced and requires but a single structure to meet all conditions of bomb hoisting and loading.

A further object of the invention is to provide a very simple and efficient structure. This structure is designedly constructed to assure rapid loading of bombs. In actual use, it has reduced the time considerably. In certain instances, a bomb may be loaded in approximately one minute as compared to approximately ten minutes heretofore required. Moreover, the possibility of leaving parts of the hoisting device about the bombs due to the difficulty of removal in cramped quarters is eliminated.

A still further object of the invention is the manner in which the bombs, irrespective of weight, may be raised with their axes parallel to the longitudinal axes of the ships to conform to the attitude of the ships. The structure is designed so that the cable fittings may be readily placed off-center whereby the bombs may be raised at an angle to the horizontal, or, in the case of the use of double hoists, these cable fittings may be placed slightly above the athwartship's center of the bombs instead of directly opposite one another on the horizontal center in order to prevent any tendency of the bombs to spin about their longitudinal axes during hoisting.

A still further object of the invention is to provide a bomb hoisting band that will be not only universally adaptable to all types of missiles to be loaded but will also facilitate the loading of the missiles in any type of airplane or ship, whether requiring inboard or outboard loading, and will provide further for quick detachment from the bombs, and without the use of tools so that limitations of space will not hamper the removal of the structure after the bombs are secured in position. Quite often the construction of the ship makes it difficult for the crew to use tools in removing the clamped structure about the bomb after it is secured in loaded position. Lack of time and the difficulty of removing the clamped structure by tools have heretofore resulted in leaving the same about the bomb. Without making proper calculations for the presence of this clamped structure about the bombs, the bombs have been released in actual combat only to find that the deflection resulting therefrom caused the loss of these bombs without the desired effect. The invention proposes a construc-

tion of bomb hoisting band that includes a plurality of parts adapted to be drawn about the bombs circumferentially and to be held tightly in position during the hoisting operation, but which, when released by a take-up device or its equivalent, will readily separate and drop from about the bombs.

Another important feature is that the structure disclosed herein is capable of universal use upon any known type of bomb for loading any design or type of plane or ship.

The employment of bomb hoisting bands embodying the present invention novelly permits attaining the important feature of economy because these bands universally fit all types of bombs or missiles and may be used to load the same on all designs and types of ships. Accordingly, different sizes and styles of loading equipment need not be carried in stock and the investment in material on hand will be reduced. Only minimum space for storage will be required which is an important factor on carriers and at outposts where space is very definitely accounted for and particularly the space allocated to the storage of equipment.

The ability to adapt the present bomb hoisting bands to all types of bombs and missiles cannot be emphasized too strongly. Numerous suspension lugs, keyways and dive bombing trunnions, and similar essential fixtures affect the location of hoisting bands on the bombs and also hinder removal of the bands. The present invention presents a construction that very effectively overcomes the difficulties of such protuberances and permits easy attachment and removal by adjustably positioning the parts to avoid the protuberances without requiring a special construction of band for any particular bomb or missile or type of ship that may be loaded.

Other objects and advantages of the invention will be readily apparent from the following detail description when taken in connection with the accompanying drawings which form a part hereof.

In the drawings:

Figure 1 is an end view of an aerial bomb having a band assembly of the single hoist shackle type embodying the invention disclosed herein, parts of the take-up plate assembly being in cross section for the purposes of illustration;

Fig. 2 is a fragmentary side view of the aerial bomb shown in Fig. 1 to illustrate one side of the band assembly in side elevation;

Fig. 3 is the view shown in Fig. 1 but with the parts of the band assembly in open position and about to be dropped from the aerial bomb that has been hoisted in position on the ship and attached, say, to the shackle connection, the locking pin being shown removed to free the hoist cable fitting;

Fig. 4 is a detail view to illustrate how the bands are slidable to bring the clips at their ends opposite the removal notches of the clip-retaining brackets in order to free the same from the upper hoisting plate assembly and allow the parts to drop from about the bomb;

Fig. 5 is an end view of substantially the same construction shown in Fig. 1 but of the double hoist shackle or rack type, parts of the take-up plate assembly being in cross section for the purposes of illustration;

Fig. 6 is also a fragmentary side view of the aerial bomb shown in Fig. 5 to illustrate in side elevation the take-up mechanism and its plate assembly and the manner of connecting the hoist

5 cable fitting thereto when a double hoist is used;

Fig. 7 is a detail side view of a clevis connection that may be used in lieu of the hoist cable fitting shown in Figs. 5 and 6;

Fig. 8 is a side view of the same;

Fig. 9 illustrates somewhat diagrammatically the manner of loading bombs to the underside or to the bomb bay of an airplane when employing the bomb hoisting band disclosed herein;

Fig. 10 illustrates the take-up reel and rod used for the cable lifting the bombs and a form of fixture that may be used to receive the end of the rod to support the same and carry the band as the bomb is lifted to its position in the ship;

Fig. 11 is a detail view of the clip retaining bracket showing how the clips at the ends of the bands are held against displacement when the bomb is lifted by the hoist cable and how this connection may be readily broken to separate the

20 parts by sliding the clips sidewise to align with the removal notches when moved inwardly or to disengage the hinged connection at the plate when moved outwardly, this latitude of disconnection being advantageous when obstruction 25 prevents the bands from being shifted in one of the directions;

Fig. 12 is a fragmentary detail view of this clip-retaining bracket illustrating how the bracket at the removal notches may be bent to 30 prevent this sidewise movement inwardly of the clips whereby the clip will be held against displacement except when moved outwardly or away from the plate assembly;

Fig. 13 is an exploded detail view of the clip 35 and the connectors, the bolts being omitted, to illustrate their assembly at a predetermined position along the straps according to the diameter of the bomb to be lifted;

Fig. 14 is a view similar to Fig. 1 but showing 40 the construction of plate and hoisting lug assembly that may be used to connect the hoisting cable fitting when the bomb is to be attached to a rack in the bomb bay;

Fig. 15 is a view similar to Fig. 2 but showing 45 the construction used in Fig. 14;

Fig. 16 illustrates a further use of the structure embodying the invention; and

Fig. 17 diagrammatically illustrates how a 50 number of bombs may be mounted in a bomb bay by the form illustrated in Fig. 16 or by any of the other forms of structure.

Although we illustrate and describe several embodiments of the invention, it will be understood at the outset that the invention may be embodied 55 in other forms and that one or more of the novel features may be employed without adopting all of the structure disclosed herein.

As illustrated in Figs. 1 to 4, inclusive, a bomb hoist band embodying the invention includes a 60 plurality of band sections 1 and 2 adapted to encircle a bomb, designated broadly as 3, and to be drawn about the bomb by a take-up mechanism 4. Connectible means in the form of plate assemblies 5 and 6 may be provided between the opposite ends of the band sections 1 and 2 for receiving these opposite ends in hinged relation. Band sections 1 and 2 may be metal straps, if so desired,

65 and, while it is not essential to the invention disclosed in so far as accomplishing certain of the novel results is concerned, these straps may be made of a metal having some resiliency or spring action so that, when flexed about the bomb circumferentially, the gripping action at the hinged connections between their ends and the

70 plate assemblies will be increased to prevent dis-

placement of the parts at these points, and so that, when the parts are released by the take-up mechanism after the bomb is secured in position in the bomb bay or other desired location, these parts will tend, due to this spring action or resiliency of the metal band sections, to separate from the plate assemblies and drop quickly from about the bomb without the further aid of tools.

Plate assembly 5 constitutes essentially an element to which the ends of band sections 1 and 2 may hingedly connect and at the same time receive a cable hoist fitting 7. It may comprise an outer plate 8 and an inner plate 9 suitably welded or otherwise secured together. Both plates 8 and 9 may be curved slightly so that their side edges rest against the periphery of the bomb 3, these side edges being turned outwardly as indicated at 10 and 11, the side edges 11 being curved into an inturned flange for receiving clips 12 adapted to be adjustably carried along band sections 1 and 2 at or near their ends.

Outer plate 8 is provided with cutaway portions 13 and is arched at 14 preferably along its medial line at the portions 15 between the cutaway portions 13. Inner plate 9 is also slightly arched at 16, which, with arching 14 of outer plate 8, forms a hole 17 to receive a removable pin 18. Pin 18 forms the swivel connection for hoist cable fitting 7 adapted to seat in any one of the cutaway portions 13. Providing a number of positions for hoist cable fitting 7 along the upper plate assembly 5 on pin 18 enables the bomb to be lifted with its longitudinal axis parallel to the longitudinal axis of the airplane. The connection can be made centrally of the upper plate assembly 5, and, if the entire structure of the bomb hoisting band is located approximately centrally of the bomb, the bomb will remain horizontal while lifted. However, locating the connection of the hoist cable fitting 7 on pin 18 on either side of the center cutaway portion 13 will cause the bomb to tilt slightly so that its longitudinal axis may be made to assume a parallel position with that of the axis of the airship to facilitate the hoisting and the attaching of the bomb.

Pin 18 may have one end curved as at 19 and grooved at 20. Curved portion 19 serves as a handle grip which may be gripped by the crew to remove the pin 18 quickly without the use of tools after the bomb is positioned in the bomb bay or under the wing and secured either to the shackle 21 as illustrated in Fig. 3, or to the rack 22 illustrated in dotted lines in Figs. 14 and 15. Groove 20 receives a spring clip 25 suitably carried by plate 8 to lock pin 18 in position to prevent accidental displacement while the bomb 3 is being lifted. This can be readily accomplished by laying the curved portion 19 against plate 8 after the cable fitting 7 is placed in the proper recess 13 and the pin 18 is inserted in hole 17. Turning curved portion 19 downwardly will bring groove 20 in spring engaging relation with clip 25 to hold pin 18 from being accidentally pushed out of position and will keep the curved part 19 from interfering with the lifting operation.

Clips 12 may be secured at one of a plurality of positions along band sections 1 and 2 at or near their ends. These ends may be provided with a number of perforations 26 to receive bolts 27 that are adapted to connect the clips 12 to the underside of the band sections, there being connectors 28 employed on the opposite side, these connectors 28 being preferably channel shaped and receiving the lock washers and nuts

- 29 within their side flanges 30. Connectors 28 provide a very sturdy fastening for clips 12 at the ends of the band sections and provide by their side flanges 30 a surface that may be tapped by a hammer or the like if the ends of these band sections fail to slide readily along the curved flanges 11 of the plate assembly 5 to bring clips 12 opposite removal notches 31 in clip-retaining brackets 32 (see Figs. 4 and 11).
- 10 Clip-retaining brackets 32 are suitably secured to outer plate 8 as by welding or the like and are provided with spaced lugs 33 that are formed by portions cut and bent up, the unbent portions 34 remaining in engagement against the upper face of plate 8. Lugs 33 are spaced apart and represent the approximate spacing of the band sections 1 and 2 when they are used in pairs as illustrated herein. In Figs. 4 and 11, three lugs 33 are shown, and hence, three positions are represented for the reception of band sections 2, but two only are employed. The third position, which may be the middle or either end position, is provided to allow for positioning of band sections 1 and 2 to avoid keyways, lugs or other protuberances that may project from the surface of the bomb. In this Fig. 4, the band sections 2 are in their full line positions shown opposite the removal notches 31 so that the clips 12 thereon will drop out of engagement with the curved side edge 11 of outer plate 8 and the band section 2 will drop free therefrom and from the bomb. It will be apparent that little space will be required to allow the clips 12 and connectors 28 at the end of each band section 2 to clear.
- 15 Line 36 illustrates, for example, a wall against which bomb 3, held by shackle 21, may be required to abut in a bomb bay so as to show the extent of the space left in which crewmen may operate to load bombs and then remove the hoisting equipment. The thin flexible band sections 2 may be worked through this space without difficulty while the small clips 12 and connectors 28 will obviously present little, if any, problem of removal.
- 20 The dotted line positions in Fig. 4 represent the band sections 2 in their positions when the band sections 2 are drawn and held about the bomb 3 during the hoisting operation. It will be apparent that lugs 33 very effectively prevent clips 12 unhooking from the curved side edges 11 and require these clips 12 to be moved sidewise either entirely outside of the clip-retaining brackets 32 or opposite the removal notches 31. As previously mentioned, band sections 1 and 2
- 25 may be, although not necessary, made of resilient or spring metal. If made of resilient or spring metal, it will be apparent that when the band sections are released after the bomb has been spotted and secured in position, they will tend to straighten themselves and thereby cause the clips 12 to unhook from the upturned side edges 11 of top plates 8 and that any side movement at the lower end of the band sections by the crewmen will cause the clips 12 to side slip and move opposite the removal notches 31 to free themselves from the lugs 33.
- 30 At the lower end, each band section 1 and 2 may also receive clips 12 secured in adjustable relation in substantially the same way. The lower plate assembly 6 may likewise be constructed the same as upper plate assembly 5, one addition being the use of, say, a lug 38 to which a take-up device 4 may be pivotally connected.
- 35 Take-up device 4 may comprise a threaded

bolt 41 pivoted to lug 38 and a nut 42 carried by bolt 41. Nut 42 is provided with a handle 43 that may be used to move nut 42 back and forth along bolt 41. Cooperating with the lower plate assembly 6 is another plate 45 that may be hingedly connected to clips 12 at the lower ends of band sections 1 in substantially the same manner as outer plates 8 of the upper and lower plate assemblies 5 and 6 connected to clips 12. This can be accomplished by placing a socket lug 46 of take-up device 4 centrally upon plate 45 and employing two clip-retaining brackets 47 close for the clips 12, the removal notches 31 being provided by the space left between the socket lug 46 and the lip-retaining brackets 47, each bracket having upturned lugs 47' similar to lugs 33 of clip-retaining brackets 32 (this being clearly shown in Fig. 6). As long as the clips 12 engage the upturned side edge 48, similar to side edges 11, the plate 45 will remain hingedly connected to these clips. Lug 46 is provided with a socket 49 to receive the spherical face 50 (Fig. 3) of take-up nut 42 when these parts are coupled together.

Plate 45 is preferably of channel shape or the like with side flanges 51. The adjacent end of the lower plate assembly 6 is adapted to lie in this channel formation between side flanges 51 of plate 45, the side flanges 51 acting as a guide to bring the take-up nut 42 into alignment with stud 46 so that spherical face 50 will readily drop into socket 49.

Figs. 1 and 2 illustrate the bomb hoisting band completely assembled about a bomb and being attached to shackle 21 carried by the airplane, the bomb having the usual lug 51' or equivalent attachment member for connection with the shackle. Fig. 3 illustrates how the parts separate after the connection is made with shackle 21. Pin 18 is removed and the take-up nut 42 is backed out of its socket 49 in lug 46. The hoist cable fitting 7 is immediately freed and the band sections 1 and 2 open and hang loosely at the bottom. Slight side movement of these band sections 1 and 2 will bring clips 12 at their upper ends opposite removal notches 31 or free of the curled edges 11 if moved the other way whereupon these clips will snap out of engagement with the upturned side edges 11 of top plate 8 and the band sections will drop to the ground.

The manner of handling the hoists and the loading of bombs either in the bomb bay or the underside of wings is illustrated in Figs. 9 and 10. The bombs may be brought on dollies 55 to the airplane, or, in the case of an aircarrier, the bombs may be brought to the ship on a conveyor (not shown). In view of the fact that the structure embodying the present invention solves the problem of loading different types of planes and bombs by the use of a single form of unit, the bomb hoist bands may be assembled upon the bombs in advance of the loading operation. Thus, the time heretofore consumed in applying the hoist mechanism about the bomb only after the type of plane and its construction for receiving the bomb are known, is saved in the actual loading operation which is important in an emergency. The hoist rod 56 is provided with a lug and pin fitting 57 at its far end for hooking into a slotted fixture 58 or the like on the plane. The opposite end of the rod 56 with its reel 59 is handled by the crew, who, after inserting the hoist cable fitting 7 in the desired recess 13 in the top plate assembly 5 and pin 18 into hole 17 and of course through fitting 7, will wind cable

60 onto reel 59. The operation is quick, although the bomb may be heavy and bulky and must be handled exceedingly carefully. The shackle 21 is connected to lug 51 and the bomb hoisting band is disconnected in the manner heretofore described.

If the weight of the bomb or its location in the bomb bay or other position on the ship warrants the use of two hoists, or, if for other desired reasons the loading operation would be expedited by the use of two hoists, the structure above described may be assembled about the bomb in the manner shown in Figs. 5 and 6. Inasmuch as the upper and lower plate assemblies 5 and 6 are substantially of the same construction, the assemblies may be used about the bombs in the manner shown in Figs. 5 and 6. Each assembly is provided with the outer plate 8 and the inner plate 9, the outer plate having cutaway portions forming recesses 13 to receive the hoist cable fitting 7 and arched portions 14 with arched portion 16 on inner plate 9 forming hole 17 to receive the removable pin 18. Hence, the lower plate assembly 6, which may in fact be properly termed the plate assembly of the take-up mechanism, is adapted also to carry a hoist fitting pin 18 so that it may be used directly with the hoist cable also.

When locating the plate assemblies 5 and 6 for double cable hoisting, as shown in Figs. 5 and 6, it is desirable that they be placed slightly above the athwartship's center of the bomb instead of directly opposite one another, say, along the horizontal diameter and 180° apart. This will prevent any tendency of the bomb to spin about its longitudinal axis during hoisting. The degree of off-centering the plate assemblies may vary and possibly need not be great as will be noted by 62 at the left-hand side in Fig. 5, which represents the difference above the athwartship's center of the bomb the plate assemblies 5 and 6 are placed.

It will be apparent that plate assemblies 5 and 6 may be positioned anywhere about periphery 45 of the bomb and that they may be positioned differently with respect to each other, this being accomplished by reason of the adjustability of clips 12 along band sections 1 and 2. By moving the clips 12 backward or forward at adjacent ends of these band sections, the plate assembly's position may readily be varied. Such adjustment of a plate assembly's position may be made without necessarily changing the opposite plate assembly. The flexibility of such adjustments is particularly advantageous on certain types of missiles that have projecting lugs, etc., that interfere with the positioning of these plate assemblies at the center and sometimes require off-centering.

It will be apparent from the construction of the bomb hoisting band disclosed that pins 18 can be quickly removed from both plate assemblies 5 and 6 and the cable fitting 7 attached, the pins 18 being replaced with their handle portions 19 turned to lie flat against the outer plates 8 and held by the spring snaps or catches 25. If time should enter into the loading period to the extent of desiring to save even the time required to remove pins 18 and attach hoist fittings 7 as each bomb is lifted and loaded in the bomb bay or under the wing of a ship, the bombs may have the bomb hoisting bands attached in advance of the loading periods and be provided with clevises 65 shown in Figs. 7 and 8. These clevises 65 may be of any desired con-

struction and may be attached by pins 18 in the same manner as the cable fittings 7. The cables 60 may then have hooks 66 carried at their ends to connect to the clevises 65. The time required to connect the cables 60 to the bomb hoisting bands during the loading periods will be therefore that which is required merely to snap hooks 66 onto clevises 65.

Whether single or double cable hoisting is employed the choice of the length of band sections 1 and 2 only requires that the combined length equal at least the circumference of the bomb with the space occupied by the plate assemblies being of course taken into consideration. It is not necessary that the straps be of equal length or that the length of the straps on one side be equal to the length of the pair on the opposite side. Various arrangements are possible. More than three positions, as shown in Figs. 4 and 11, for the band sections on each side may be provided if it so desired, so as to give any desired latitude in placing the band sections about the bombs to avoid protruding lugs, trunnions, keyways, etc. The protuberances heretofore caused considerable annoyance and made the task of attaching the hoisting mechanism quite difficult at times. The extra position or positions for these band sections on each side allows a greater choice in positioning the band sections so as to avoid such protuberances. Moreover, it is not essential that the band sections on each side align with the band sections on the opposite side. It is only necessary that the plate assemblies be firmly held against the surface of the bombs and that the load be fairly well distributed.

Fig. 13 illustrates the relative ease of attaching the clips 12 at different positions along or near the ends of the band sections so that the structure can be readily made to fit different diameter bombs. The attendant may hold clip 12 in the palm of one hand with the bolts 27 inserted from the underside through the two holes therein, then lay the band section thereover with the proper holes 26 thereof in alignment with the holes in the clip and with the shanks of the bolts passing therethrough, and then place connector 28 thereover and tighten the lock nuts 29 with their washers in place upon bolts 27. This operation is simple and can be accurately carried out without much difficulty.

Figs. 14 and 15 illustrate the bomb hoisting band as applied to single cable hoisting where racks are used to receive the bombs. The structure is substantially the same as previously described except for the upper plate assembly 5. This assembly is eliminated and a single plate 70 may be used instead. Plate 70 may be of the same shape and construction as outer plates 8 with the omission of the recesses 13 and raised portions 14 to form the holes 17. Hoisting lugs 71 and 72 may be used and a space 73 may be provided therebetween to receive cable fitting 7. A removable locking pin 74 having a tapered end may be inserted in holes in lugs 71 and 72 and through fitting 7. The tapered fit will hold this locking pin 74 in position and prevent its accidental displacement.

The construction of the plate assemblies may be changed, as will be thus seen, without necessarily departing from the invention in so far as the adoption of certain novel features disclosed herein is concerned. The structure used will depend upon the particular conditions under which the loading may be carried out, or the kind or

type of rack or shackle that may be used. Hence, it is to be understood that any departure on the design of the plate assemblies will not necessarily avoid the scope of the invention. The feature of ready adaptability to any type of missile and design or type of airplane, which the structure disclosed herein seeks to accomplish, is novel and of considerable importance in devices of this kind. Likewise, the features of speed of 10 application and removal, and the fact that tools are not required to effect removal, are also novel and important.

After the cable fitting is removed either by removing pins 18 or by disconnecting hooks 66 from clevises 65, the mere backing down of take-up nut 42 by handle 43 will loosen the parts and break the connections between them to the extent, if moved sufficiently, of readily separating and falling from the bomb after it is hoisted and secured in position. However, when the parts are drawn about the bomb, they will be firmly held and it will be impossible for the band structure to shift or become loose during the hoisting operation.

Fig. 16 illustrates another example of double hoisting, when desired, by the use of two of the type of plates illustrated at 5 and several of the bands 2 forming a cradle-like lift for the bomb. These plates 5 may be placed slightly above the athwartship's center of the bomb, and the bands 2 may have their clips 12 hooked into the curved flanges 11 of outer plate 8 opposite locking lugs 33 in the same manner as previously described, so that these clips 12 will hold in their hooked relation with the curved flanges 11 and be prevented from being inadvertently displaced from the curved flanges 11 except by being side slipped beyond the lugs 33. If desired, the unbent portions 34 may also be bent up slightly, as shown in Fig. 12, to prevent the clips 12 from side slipping free of lugs 33 in an inward direction. This is, of course, optional.

Cables 60 are attached by fittings 7 being secured upon pins 18 in any of the openings 13, 45 the pins 18 being locked by the groove 20 of curved portion 19 engaging clips 25 or the like. The cables then lift the bomb or other object to its place in the bomb bay, as illustrated in Fig. 17, or under the wings of the ship. The manner in which the loading takes place in the bomb bays is illustrated in Fig. 17, although this may vary. The cables 60 entrain over sheaves 65 which may be carried by pin fittings 66 hooking into a slotted fixture 67, suitably disposed in or above the bomb bay. Any number of bombs may be supported and mounted in their proper positions in the bomb bay. Hoisting the bombs in this manner will not interfere with the upper bombs which are first loaded. Suitable bomb doors 68 are provided for the bomb bay in the usual way, but it will be understood that the construction of the bay, or the way in which the bombs are mounted, may be varied without departing from the scope of the invention.

The manner of hoisting illustrated in Fig. 16 is generally suitable for use where the lift is not great and the bomb will readily remain cradled in bands 2 without slipping therefrom. Where the lift is considerable, or where there is disturbance as by the rolling of a ship, extending the bands completely about the bomb, as illustrated in Figs. 1 to 16, inclusive, may be more desirable. The form illustrated in Fig. 16 permits adaptation of the structure shown to any size or shape of bomb, and likewise avoids interference with

11

the expansion lugs, keyways and dive bombing trunnions.

Without further elaboration, the foregoing will so fully explain the gist of our invention that others may, by applying current knowledge, readily adapt the same for use under varying conditions of service, without eliminating certain features, which may properly be said to constitute the essential items of novelty involved, which items are intended to be defined and secured to us by the following claims.

We claim:

1. A band assembly for a bomb hoist comprising band sections of resilient spring metal adapted to be drawn circumferentially and tightly about the bomb, members disposed longitudinally of said bomb to which the ends of said band sections are connected, inter engaging flanges on said members and said band sections, the spring resiliency of the metal of said band sections tending to increase the engagement between said flanges when said band sections are drawn tightly about the bomb, and interlocking means to prevent disengagement between said flanges except by an initial sidewise movement thereof.

2. A band assembly for a bomb hoist comprising a plurality of band sections adapted to be drawn circumferentially about a bomb, there being portions of clip formation at the ends of said band sections, connectible means between the adjacent ends of said band sections for receiving said clip-formed portions, take-up means for drawing and holding said band sections about the bomb, clip-retaining brackets on said connectible means for preventing displacement of said clip-formed portions when said band sections are drawn and held about the bomb by said take-up means, said clip-retaining brackets having provisions for releasing said clip-formed portions on said band sections from said clip retaining brackets when said take-up means releases said band sections from about the bomb.

3. A band assembly for a bomb hoist comprising a plurality of band sections adapted to be drawn circumferentially about a bomb, there being portions of clip formation at the ends of said band sections, connectible means between the ends of adjacent band sections for receiving said clip-formed portions, and clip-retaining brackets on said connectible means for preventing displacement of said clip-formed portions when said band sections are drawn about the bomb, said clip-retaining brackets having notches therein for the removal of said clip-formed portions.

4. A band assembly for a bomb hoist comprising a plurality of band sections adapted to be drawn circumferentially about a bomb, there being portions of clip formation at the ends of said band sections, connectible means between the ends of adjacent band sections for receiving said clip-formed portions, and clip-retaining brackets on said connectible means for receiving said clip-formed portions by a slidable movement of the latter in a direction longitudinally of the bomb, there being elements on said brackets for preventing outward displacement of said clip-formed portions when the latter are opposite said elements.

5. A band assembly for a bomb hoist comprising a plurality of band sections adapted to be drawn circumferentially about a bomb, clips carried by said band sections, connectible means between the ends of adjacent band sections having portions receiving said clips in hinged relation, mechanism for drawing said band sections cir-

cumferentially about the bomb, and means for preventing displacement of said clips from said receiving portions while said band sections remain in a predetermined position with respect to said connectible means.

6. A band assembly for a bomb hoist comprising a plurality of band sections adapted to be drawn circumferentially about a bomb, clips carried by said band sections, connectible means between the ends of adjacent band sections having portions receiving said clips in hinged relation, mechanism for drawing and holding said band sections circumferentially about the bomb, there being means to provide relative adjustability between said band sections and said connectible means whereby band sections of different lengths for the same or different size of bombs may be used.

7. A band assembly for a bomb hoist comprising a plurality of band sections adapted to be drawn circumferentially about a bomb, clips carried by said band sections, plate assemblies between the ends of adjacent band sections having portions for receiving said clips in hinged relation, one of said plate assemblies having separable parts, a take-up bolt and nut on one of said parts, a socket carried by the other part for receiving said take-up nut whereby said band sections may be drawn and held about the bomb, and a cable fitting for at least one of said plate assemblies.

8. A band assembly for a bomb hoist comprising a plurality of band sections adapted to be drawn circumferentially about a bomb, plate assemblies to which said band sections are connected at opposite ends, one of said plate assemblies having separable parts, a take-up mechanism carried by said separable parts whereby said band sections may be drawn and held about the bomb, a cable fitting for at least one of said plate assemblies, a removable locking pin for attaching said cable fitting in position, said pin having a readily grippable portion adapted to be used to remove said pin but to be swung when not used in a locking position, and a movable clasp for engaging said pin to hold it in said locking position.

9. A band assembly for a bomb hoist comprising circumferential band sections, adjustable means at opposite ends of said band sections for detachably connecting said band sections circumferentially about a bomb, a take-up mechanism for drawing and holding said band sections about the bomb, a cable fitting, a removable locking pin for attaching said cable fitting in position, said pin having a readily grippable portion adapted to be used to remove said pin but to be swung when not used in a locking position, and a clasp for engaging said pin to hold it in said locking position.

10. A band assembly for a bomb hoist comprising circumferential band sections adapted to be drawn circumferentially about a bomb, plate assemblies to which said band sections are connected, a take-up mechanism for drawing said band sections about the bomb, a cable fitting, and a removable locking pin to which said cable fitting is pivotally attached, at least one of said plate assemblies having a series of spaced elements receiving said pin and between which elements spaces are provided to receive said cable fitting in one of a number of positions on said plate assembly.

11. A bomb hoisting band assembly comprising a pair of spaced spring bands to encircle the bomb, each of said bands being in sections, an

12

elongated plate-like member at the ends of said sections extending longitudinally of the bomb and beyond the bands of the pair, clips adjustable on and adjacent the ends of said band sections arranged hingedly to connect in adjusted relation with and along the edges of said member, a take-up device associated with one of said members operable simultaneously and independently of the hoisting cable to tighten and hold said bands and plates around the bomb during hoisting, and a hoisting cable connection engageable with one of said members at different positions along the length thereof.

LOUIS F. MAHAN.
